Fraser, Myers & Manley.

UNITED STATES PATENT OFFICE

ROWLAND T. WALES, OF NEW ROCHELLE, NEW YORK

MOLD FOR CONCRETE

Application filed November 12, 1925. Serial No. 68,508.

The present invention relates to molds for concrete and the like and aims to provide certain improvements therein. More especially it relates to improvements in the construction of the plates or panels which constitute the major facing of such mold and means for holding them in position.

Molds for concrete as commonly used in present day practice comprise panels formed of boards approximately $\frac{3}{4}$ ths to $\frac{7}{8}$ ths of an inch thick and from four to ten inches in width. These panels, when subjected to repeated wetting and drying, because of their dimensions, become warped and buckled to such an extent as to create large cracks between the boards and provide a much deformed mold facing.

Among the objects of the invention are the following: (1) to substantially lessen the weight of the panels; (2) to reduce the bending strains of the battens; (3) to provide a panel in which any part of the face thereof can be quickly and cheaply replaced if it becomes damaged or deformed; (4) to reduce the expansion and contraction of such parts to a negligible amount; (5) to make such parts adaptable for thorough saturation with oil; and (6) to substantially cheapen the costs of such panels.

The foregoing and various other objects of the invention which will be made apparent as the description proceeds, I accomplish by making the panels substantially entirely of wood, the face thereof being formed of comparatively thin boards mounted on battens, and said panel being reinforced when mounted upon the supports or studs to form a mold, by reinforcing members which span the battens and co-operate with the locks on the studs to hold the panels in place thereon.

In the accompanying drawing which shows a preferred embodiment of my invention.

Figure 1 is a top plan view of a portion of a concrete wall and mold.

Fig. 2 is a vertical section taken on the plane of the line 2—2 of Fig. 1.

Fig. 3 is a perspective view of the panel as viewed from the rear.

Fig. 4 is a horizontal section taken on the line 4—4 of Fig. 3.

Referring to the drawing let A indicate a portion of a concrete wall or structure formed within a mold, the major portion of which is provided by panels B mounted upon supports or studs C fitted with tie rods D and locks E adapted for holding the panels in place upon the supports. The specific character of the studs C and locks E herein illustrated are described in detail in my co-pending application Serial No. 475,340, filed June 6, 1921, which has eventuated into Patent No. 1,564,651, dated December 8, 1925.

According to the present invention the panels B, which are usually rectangular in form, are preferably formed substantially entirely of wood and consist of rigid frames formed by horizontal members F and vertical members G. Laterally spaced within the frame are rigid battens H, and the facing of the panel is provided by comparatively thin narrow boarding J of a thickness not exceeding one-half inch and a width not exceeding two inches secured in any preferred manner to said frames and battens. Any of these boards J, it will be appreciated, can be quickly and cheaply replaced if it ever becomes damaged from any cause whatever.

A panel so constructed, it will be realized, will not have adequate lateral strength, but this is supplied by reinforcing members K which are adapted to laterally span the battens H and co-operate with the locks E to hold the panels in place upon the supports. In order that these reinforcing members K may have maximum strength with minimum weight, I prefer to make them of angle iron or the like. It is also preferable to form these members separately from the panel and have them adapted to be detachably hung on the panel while it is being hoisted to a high position.

For the purpose of preventing the top and bottom edges of the panel frame from becoming injured through rough usage I prefer to sheath said edges with metal, as indicated at M.

In use the panels B are first mounted upon

the supports or studs C behind the locks E. One leg of the angle iron K is then slipped or positioned between the locks and the rear of the panels and spanning the battens there-
5 of, after which the locks E are operated to clamp the member K in position. When thusly mounted the angle iron members K provide adequate reinforcement to maintain the panel against transverse buckling.
10 When dismantling the mold, the locks are opened, the members K withdrawn, and the panel then withdrawn from the supports.

From the foregoing description it will be appreciated that the present invention ac-
15 complishes all of the objects enumerated, and in addition thereto will reduce the cost of constructing concrete walls due to the saving in the initial cost of such panels, and in their upkeep, and further, because of their
20 light weight a workman can carry two panels where at present he carries but one.

The invention, it is to be understood, may receive other embodiments from that herein specifically illustrated and described with-
25 out departing from the spirit of the in-
vention.

What I claim is:

A mold for concrete, comprising supports, panels mounted between said supports, sepa-
30 rate panel reinforcing members between the supports and extending transversely thereof, and adjustable means cooperating with the supports for holding the reinforcing members against the panels, said reinforcing
35 members each having a part overlying the adjustable means and adapted to be sup-
ported thereby prior to pressure being creat-
ed between said means and the panel.

In witness whereof, I have hereunto signed
40 my name.

ROWLAND T. WALES.
